UNITED STATES PATENT OFFICE.

JOHN F. DORNFELD, OF CHICAGO, ILLINOIS.

DUMPING-FLOOR.

No. 850,214.

Specification of Letters Patent.

Patented April 16, 1907.

Application filed February 17, 1905. Serial No. 246,115.

To all whom it may concern:

Be it known that I, JOHN F. DORNFELD, a citizen of the United States, residing at Chicago, in the county of Cook and State of Illinois, have invented certain new and useful Improvements in Dumping-Floors, of which the following is a specification.

This invention refers to dumping-floors for use in malt-kilns and other places where it is desirable quickly to clear a floor of any granular substance thereon, and relates to the various improvements in such a floor hereinafter pointed out.

In the accompanying drawings, Figure 1 is a fragmental sectional view through a dumping-floor embodying the features of this invention. Fig. 2 is a sectional view through said floor, taken on dotted line 2 2 of Fig. 1. Fig. 3 is a fragmental sectional view through one of the floor-sections. Fig. 4 is a detail view of the means for supporting one of the end sections of the floor.

This improved dumping-floor is made up of a number of sections extending from side to side of the room and of identical construction, except in the case of the two end sections, which end sections, as will hereinafter appear, differ slightly from the intermediate sections and from each other. The intermediate floor-sections 1 comprise end pieces 2, cross-pieces 3 and 4, longitudinal side pieces 5, floor-brackets 6, extending parallel with the cross-pieces 3 and 4, and a perforated floor-plate 7, all rigidly secured together. The floor-brackets 6 are each formed of a strip of band-steel twisted and bent at each end to provide attaching-ears 8, adapted to be riveted to the side pieces 5 and flat horizontal portions 9, to which the floor-plate 7 is riveted, as shown in Fig. 4. By this construction of floor-brace I obviate the necessity of providing special means for attaching the floor-plate 7 to the framework of the section. The pieces 2, 3, and 4 are provided with hubs 10, through which passes a square shaft 11, said shaft extending from one side of the room to the other and projecting through one wall of said room into position to be engaged by a wrench or similar device for rotating it. The shaft 11 extends somewhat to one side of the center of gravity of the section. A plate 12, set into the wall at each side of the room, provides a bearing for the hub 10 of the adjacent end piece 2, and between its ends the floor-section is supported at suitable inter-

vals in its length upon standards 13, suitably mounted upon girders 14, extending transversely beneath the sections of the floor. Each of said standards 13 is provided at its upper end upon one side with a semicylindrical bearing 15 for supporting the hub 10 of one of the cross-pieces 4. Upon the other side of the standard 13 is formed a seat 16, upon which a locking-arm 17 is adapted to rest. Each of the pieces 2 and 4 is provided with such a locking-arm 17, said arm being pivotally mounted upon a stud 18 on said piece. From the bearing-plate 12 at each side of the room projects a stud 19, adapted to support the locking-arm 17 of the adjacent end piece 2. When the intermediate floor-sections 1 are in their normal horizontal position, the locking-arms 17 project far enough beyond the sides of their respective sections to underlie and support the near side of the adjacent section. It will thus be seen that the tilting of one of the sections 1 successively withdraws the supports for all the sections to one side of the first-mentioned section, automatically bringing about a tilting of said sections.

The section 1^a at one end of the floor instead of being pivotally mounted at a point between its sides is pivotally mounted at one side by means of perforated ears 20, fixed to the framework of the section and rotatably supported upon sleeves 20^a, surrounding a shaft 21, extending from side to side of the room. Upon the girders 14 is pivotally mounted a series of cam-levers 22, each carrying at its upper end a roller 23, adapted to lie beneath and support the swinging side of the end section 1^a and the near side of the adjacent intermediate section 1. A connecting-rod 24 pivotally connects each of said cam-levers with a crank-arm 25, fixed upon the shaft 21. One end of the shaft 21 extends through the wall of the room into position to be engaged by a wrench for turning it. The floor-section at the opposite side of the room is substantially like the intermediate sections 1, the locking-arm 17, however, being omitted.

The floor-plates 7 at their side edges extend beyond the side pieces 5, forming side flanges upon each side of each section, one of which flanges may be depressed or bent in rabbet form to underlie the flange of the next adjacent section, forming a supporting seat or bearing for said adjacent section, and thereby

keeping the upper surface of all of the plates in a plane for convenience in sweeping or passing over the floor.

When it is desired to dump the floor, the 5 shaft 21 is rotated by means of a wrench or in any other convenient manner to withdraw the cam-levers 22 from beneath the section 1^a and the adjacent section 1, permitting said section 1^a to tilt downward upon its 10 shaft 21 and said section 1 to tilt upon its shaft 11. The tilting of the section 1 withdrew the locking-arms 17 from beneath the next succeeding section 1, permitting said latter section also to tilt by gravity, and so 15 on throughout the series of floor-sections. The sections are restored to a horizontal position one at a time in reverse order by rotating the shafts 11 from one end of said shafts until the end section 1^a is reached. The latter section 20 is raised by rotating the shaft 21 to move the cam-levers 22 upwardly upon their pivots, said levers in their movement lifting the section into a horizontal position. The movement of the levers 22 is continued until 25 the rollers 23 of said levers underlie the adjacent sides of said section 1^a and the adjacent intermediate section 1.

The embodiment herein shown of this invention is susceptible of various modifications without departing from the spirit and scope of the invention, wherefore I desire to have it understood that I do not limit myself to the precise details herein set forth.

I claim as my invention—

35 1. A dumping-floor comprising a series of pivoted sections, each of said sections having pivotally connected thereto a locking-arm arranged to move with its section and adapted, when the section is in a horizontal position, to support the next adjacent section and means for supporting the free end of said arm.

2. A dumping-floor comprising two pivotally-mounted sections, a pivoted locking-arm

45 on one section adapted to underlie and support the other section when both are horizontal, and means for supporting the free end of said locking-arm.

3. A dumping-floor comprising a movably-mounted section, a stationary member, and 50 means for moving said section comprising a cam-lever pivotally mounted on said stationary member and adapted to bear against said section, and means for pivotally moving said lever.

4. A dumping-floor comprising two pivotally-mounted sections, and means for supporting said sections comprising a pivoted lever adapted to underlie said sections.

5. A dumping-floor comprising two pivotally-mounted sections, and means for supporting said sections comprising a pivoted lever provided at its free end with a roller adapted to underlie said sections.

6. In a dumping-floor, in combination, a 65 floor-section; means for pivotally supporting said floor-section comprising a standard; means for supporting the unbalanced weight of said section; an arm pivoted to said section adapted to support the unbalanced 70 weight of an adjacent section; and means on said standard for supporting the free end of said arm.

7. In a dumping-floor, in combination, a 75 floor-section; a shaft fixed thereto and located somewhat at one side of the longitudinal center of said section; means for rotatably supporting said shaft comprising a standard; means for supporting the unbalanced weight 80 of said section; a locking-arm pivoted to said section and adapted to support the unbalanced weight of an adjacent section; and a seat on said standard adapted to support the free end of said arm.

JOHN F. DORNFELD.
